No. 880,283.

PATENTED FEB. 25, 1908.

F. M. DALE.

HALL RACK.

APPLICATION FILED JULY 15, 1907.

UNITED STATES PATENT OFFICE.

FLORA M. DALE, OF WILKINSBURG, PENNSYLVANIA.

HALL-RACK.

No. 880,283.

Specification of Letters Patent.

Patented Feb. 25, 1908.

Application filed July 15, 1907. Serial No. 383,840.

To all whom it may concern:

Be it known that I, FLORA M. DALE, a citizen of the United States, residing at Wilkinsburg, in the county of Allegheny and State of Pennsylvania, have invented a new and useful Improvement in Hall-Racks, of which the following is a specification.

This invention relates to an improvement in hall racks and the object of the invention 10 is an article of furniture adapted to receive umbrellas, rubbers, hats, coats and the like.

A further object of the invention is a device of this kind which will inclose the racks thereby hiding from view the hats, coats, 15 umbrellas, etc. and a still further object of the invention is a device of this kind adapted especially for use in narrow halls or in any location where a saving of space is necessary.

20 The invention consists also of the novel features of construction, hereinafter fully described, pointed out in the claims and shown in the accompanying drawings, in which,

Figure 1 is a perspective view of the hall 25 rack closed. Fig. 2 is a perspective view of the rack open, a portion of a vertical partition being broken away.

In these drawings A represents a casing which at the front is provided with a hinged 30 door B, of comparatively narrow width and a sliding door C formed in two sections 1 and 2 the latter section 2 being of substantially the same width as the door B and the section C being of a width approximately equal to 35 one-half of the length of the casing A.

At the front and upon each side of the casing are arranged two corner standards D and the end of the casing A adjacent the door C is vertically slotted immediately to the rear 40 of the corner standard D at that end of the casing which standard forms a guide for the front surface of the door C as it slides open and shut, and the standard also serves as a shield hiding the slot from view when the 45 casing A is viewed from the front.

Within the casing is a vertical partition E dividing the casing into two compartments within which are arranged suitable hooks F of any desired kind and within one of these 50 compartments is arranged a box G provided with a drawer G' for receiving gloves and similar small articles and upon the top of the box is placed a drip pan H within which umbrellas may be stood. The lower portion of 55 the casing is divided off by a horizontal plat-

form J upon which the box G rests and which also supports the lower edge of the partition E, which partition also forms or may be made to form, one side of the said box.

Access is gained to the lower portion of the casing A by means of an upwardly open hinged lid K and in this portion or compartment of the casing is arranged a mirror L. Hangers M of any desired kind are also carried by the front of the casing A at the sides of and above the doors so that guests making but brief calls can hang hats and coats thereon without opening or disturbing the rack proper.

It will be obvious that in opening the rack the door B may be swung outwardly upon its hinges while the door C slides outwardly through the slide above mentioned until the section 1 has cleared the casing and may then be swung back as shown in Fig. 2. This permits the opening of the entire front of the rack and at the same time permits use of the rack in a narrow hall way where it might be inconvenient to swing outwardly doors of sufficient width to open the entire front. It also allows for the use of a sliding door where owing to the location of the rack adjacent the end of the hall it would not be possible to move outwardly a sliding door of the width used and formed of one piece. This construction therefore combines the advantages of both the hinge and sliding doors and at the same time adapts the rack for use in a hall where but a limited amount of space is available.

Having thus fully described my invention, what I claim as new and desire to secure by Letters Patent, is:—

1. A hall rack consisting of a casing having a vertical slot formed in one end adjacent the front of the casing, a front door of narrow width hinged to the opposite end of the casing, and a slideable door formed of two sections hinged together, one of said sections being equal in width to the hinged door, the said door sliding in the slot as and for the purpose mentioned.

2. A device of the kind described comprising a casing, said casing being open at the front and slotted vertically at one end, corner standards carried by said casing, one of said standards forming the front edge of said slot, a hinged door and a sliding door consisting of two hinged sections, said sliding door working through said slot, the corner

standard adjacent the slot forming a guide for said door as and for the purpose described.

3. A hall rack of the kind described consisting of a casing divided into compartments, means within said casing for holding articles of wearing apparel, said casing being open at the front and vertically slotted at one end, a hinged door having a width substantially equal to one-fourth of the length of the casing, a sectional door slideable in said

slot and adapted to close the remainder of the casing the sections comprising said slideable door being hinged together and one of said sections being of the same width as the 15 hinged door and when the doors are closed resting adjacent thereto.

FLORA M. DALE.
